UNITED STATES PATENT OFFICE

EMILE ERICSON, OF PELHAM, NEW YORK, ASSIGNOR TO PRAGER CO., INC., A CORPORATION OF NEW YORK

DESIGN FOR WALL PAPER OR SIMILAR ARTICLE

Application filed September 2, 1931. Serial No. 40,991. Term of patent 3½ years.

To all whom it may concern:

Be it known that EMILE ERICSON, a citizen of the United States, residing at Pelham, N. Y., in the county of Westchester and State of New York, has invented a new, original, and ornamental Design for Wall Paper or Similar Article, of which the following is a specification.

In the accompanying drawing:

The figure is a surface view of a piece of wall paper or similar article showing the design. The area within the dot and dash lines, EF and GH represent one complete

unit of design. The repeats are arranged at the sides EF and GH. At the edges EG and FH the design extends completely to the edges of the wall paper. The area ABC and D is a detail of the background of the design. This background is extended completely over the entire design but only a small portion is shown on the drawing.

I claim:

The ornamental design for wall paper or similar article as shown and described.

In testimony whereof I affix my signature.

EMILE ERICSON.
